UNITED STATES PATENT OFFICE

116,640

DESIGN FOR A HAT

Max Solash, Linden, N. J.

Application August 2, 1939, Serial No. 86,423

Term of patent 7 years

To all whom it may concern:

Be it known that I, Max Solash, a citizen of the United States, residing in Linden, in the county of Union and State of New Jersey, have invented a new, original, and ornamental Design for a Hat, of which the following is a specification, reference being had to the accompanying drawing, forming part thereof, in which:

I claim:

The ornamental design for a hat, as shown.

MAX SOLASH.
